JAMES E. DENTON, OF IRVINE, KENTUCKY, ASSIGNOR OF ONE-FOURTH TO JOHN A. WALLACE AND BETTY A. WALLACE, BOTH OF IRVINE, KENTUCKY

ADJUSTING OR TUNING DEVICE FOR VARIABLE CONDENSERS

Application filed January 4, 1930. Serial No. 418,596.

This invention relates to variable condensers of the type used in radio receiving sets, and has for one of its objects to provide a novel and simple device through the medium of which the movable plates of a plurality of condensers may be independently or simultaneously adjusted.

To attain the foregoing and other objects, the nature of which will appear as the description proceeds, the invention comprehends the provision of a device of the character stated which shall embody a shaft for the movable plates of each condenser, the shafts being concentrically related and capable of being turned independently, knobs secured to the shafts to permit them to be turned independently and means by which the knobs may be connected together when it is desired to turn the shafts simultaneously.

The invention is hereinafter more fully described and claimed, and illustrated in the accompanying drawings, wherein:

Figure 1 is a view partly in side elevation and partly in vertical section illustrating the application of my condenser tuning device;

Figure 2 is a view partly in top plan and partly in horizontal section of the tuning device;

Figure 3 is a view in front elevation of the tuning device, and

Figure 4 is a sectional view taken on the vertical plane indicated by the line 4—4 of Figure 3.

Referring in detail to the drawings, 1 designates the panel of a radio receiving set, and 2 a housing for a plurality of variable condensers. The housing 2 extends rearwardly from the panel 1, and it may be secured at its front end to the inner side of the panel in any suitable manner. The housing 2 is open at its front end and closed at its rear end. The condensers, of which some of the movable plates 3 are only shown, will be arranged within the housing one in rear of the other.

The tuning device comprises a shaft 4 which extends longitudinally through the housing 2, and is journaled at its rear end in

a bearing opening 5 in the rear wall 6 of the housing. The front end portion of the shaft 4 passes through an opening 5a which is formed in the panel 1 and is larger than and axially aligned with the bearing opening 5. The shaft 4 is provided at its rear end with a head 4a, which contacts with the rear side of the housing wall 6, and it is provided at its front end with a knob 7 which is spaced from the front side of the panel 1. A hollow shaft 8 is rotatably mounted upon the shaft 4, a hollow shaft 9 is rotatably mounted upon the shaft 8, a hollow shaft 10 is rotatably mounted on the shaft 9, and a hollow shaft 11 is rotatably mounted upon the shaft 10. Knobs 12, 13, 14 and 15 are secured to the outer ends of the shafts 8, 9, 10 and 11, respectively, and they are arranged one in rear of the other between the panel 1 and knob 7. The shafts 8, 9, 10 and 11 pass through the openings 5a of the panel 1 with the shaft 11 in light contact with the wall of the opening, and they extend rearwardly beyond each other with the shaft 8 terminating short of the rear end of the shaft 4.

The movable plates 3 of one of the condensers are fixed to that portion of the shaft 4 located rearwardly beyond the shaft 8, and the movable plates of the other condensers are fixed to the extended portions of the shafts 8 to 10. As the head 4a contacts with the rear side of the housing wall 6, and as the knobs 12 to 15 are arranged between the panel 1 and knob 7 and contact with these parts and with each other, the shafts 8 to 11 are held against endwise displacement.

The knobs 7 and 12 to 15 are in the form of discs and may be secured to their respective shafts in any well known or appropriate manner. The knobs 7 and 12 to 15 gradually increase in diameter rearwardly and in the order named, and their edges are beveled and arranged in alinement. The knobs 7 and 12 to 15 will be each provided at its edge with the usual scale, the zero marks 16 of the scales only being shown. The knobs 7 and 12 to 15 are provided in their edges with notches 17 which

extend transversely thereof and are located near the zero marks 16 and aline with each other when the zero marks are in alinement. A latch bar 18 has its lower end pivoted, as 5 at 19, in the notch 17 of the knob 7, and is adapted to be swung into and out of engagement with the notches of the knobs 12 to 15. The width of the latch bar 18 is, as clearly shown in Figure 4, equal to the 10 depth of the notches 17, so that the latch bar will not, when in active position, project beyond the peripheries of the knobs 7 and 12 to 15, and the thickness of the latch bar is, as shown in Figure 3, substantially 15 equal to that of the width of the notches so that the latch bar will, when in active position, contact with the side walls of the notches to prevent any relative movements of the knobs and to prevent the accidental 20 movement of the latch bar from active into inactive position. The latch bar 18 is provided at its upper free end with an upwardly directed extension 20 which provides a finger grip through the medium of which 25 the latch bar may be readily swung out of the notches 17 of the knobs 12 to 15, the finger grip extending above the disc 15 to permit it to be easily grasped. The latch bar 18 is pivoted to the knob 7 near the front 30 end of the notches 17 of this knob, as shown in Figure 4, so as to permit it, when in inactive position, to extend across the front side of this knob and thus occupy a position which will prevent its interfering with 35 the turning of this or the other knobs.

It should be apparent from the foregoing description, taken in connection with the accompanying drawings, that the respective shafts carry the movable plates of the 40 respective condensers, that when the latch bar is in engagement with all of the knobs, the shafts and knobs are locked together and the movable plates of the condensers may be simultaneously adjusted, and that when 45 the latch bar is out of engagement with the knobs, the shafts and knobs are free for independent movement and the movable plates and the containers may be independently adjusted.

50 While I have described the principle of the invention together with the device which I now consider the preferred embodiment thereof, it is to be understood that the structure shown is merely illustrative and 55 that such changes may be made, when desired, as fall within the scope of the invention as claimed.

I claim:

1. An adjusting or tuning device for 60 variable condensers, comprising a series of concentrically related and independently turnable shafts, each shaft carrying the movable plates of a condenser, knobs secured to the shafts to permit them to be turned independently and provided with peripheral 65

notches, and a latch bar pivotally secured at one end in the notch in one of the knobs for movement into and out of the notches of the other knobs, the latch bar being adapted when in the notches of all of the knobs to secure the knobs together to permit the shafts to be simultaneously turned. 70

2. An adjusting or tuning device for variable condensers, comprising a series of concentrically related and independently turnable shafts, each shaft carrying the movable plates of a condenser, knobs secured to the shafts to permit them to be turned independently, the knobs being arranged one in rear of the other and gradually increasing in diametrical dimension from front to rear, the knobs being provided with peripheral notches, and a latch bar pivoted at one end in the notch of the foremost knob and movable into and out of the notches of the other knobs, the latch bar being adapted when in the notches of all of the knobs to secure the knobs together and thus permit the shafts to be turned simultaneously. 75 80 85

3. An adjusting or tuning device for variable condensers, comprising a series of concentrically related and independently turnable shafts, each shaft carrying the movable plates of a condenser, knobs secured to the shafts to permit them to be turned independently, the knobs being arranged one in rear of the other and gradually increasing in diametrical dimension from front to rear, the knobs being provided with peripheral notches, the knobs being provided at their peripheries with zero marks and the notches being arranged close to said marks to cause them to aline when said marks are alined, a latch pin pivoted at one end in the notch of the foremost knob and adapted to be moved into and out of the notches of the other knobs, the latch bar when in the notches of all the knobs securing the knobs together to permit the shafts to be simultaneously adjusted, and a finger piece carried by the free end of the latch bar and extending above the largest knob when the latch bar is in the notches of all the knobs. 90 95 100 105 110

4. An adjusting or tuning device for variable condensers, comprising a series of concentrically related and independently rotatable shafts each carrying the movable plates of a condenser, knobs secured to the shafts to permit them to be turned independently, the knobs being provided with notches formed in and extending transversely of their peripheries, the knobs being arranged one in rear of the other and gradually increasing in diametrical dimension from front to rear, and a latch bar pivoted at one end in the notch of the foremost knob and movable into and out of the notches of the other knobs, the latch bar having a width equal to the depth of the notches so as not to project beyond the peripheries of the 115 120 125 130

knobs when engaged in the notches, and the latch bar being provided at its free end with an extension projecting above the periphery of the rearmost knob and providing a finger grip by means of which the latch bar may be withdrawn from the notches of those knobs located rearwardly of said foremost knob.

5. An adjusting or tuning device for variable condensers, comprising a series of concentrically related and independently rotatable shafts each carrying the movable plates of a condenser, knobs secured to the shafts to permit them to be turned independently, 10 the knobs being provided with notches formed in and extending transversely of their peripheries, the knobs being arranged one in rear of the other and gradually increasing in diametrical dimension from front to rear, and a latch bar pivoted at one end in the notch of the foremost knob and movable into and out of the notches of the other knobs, the latch bar having a width equal to the depth of the notches so 15 as not to project beyond the peripheries of the knobs when engaged in the notches, the latch bar being provided at its free end with an extension projecting above the periphery of the rearmost knob and providing a finger grip by means of which the latch bar may be withdrawn from the notches of those knobs located rearwardly of said foremost knob, the latch bar having a thickness equal to the width of the notches 20 so as to establish such contact with the side walls of the notches as to prevent it from accidental displacement from the notches, and the latch bar being pivoted near the front end of the notch of said foremost knob so as to permit it to occupy a position in front of this knob when it is withdrawn 25 from the notches.

In testimony whereof I hereunto affix my signature.

45 JAMES ERWIN DENTON.
